WALTON L. WOODY, OF SHAKER HEIGHTS, AND RANNEY J. THOMPSON, OF EAST CLEVELAND, OHIO, ASSIGNORS TO NATIONAL MALLEABLE AND STEEL CASTINGS COMPANY, OF CLEVELAND, OHIO, A CORPORATION OF OHIO

MOLD DUMPING APPARATUS

Application filed October 1, 1929. Serial No. 396,474.

This invention relates to molding operations and is more particularly concerned with the dumping of molds to release the castings contained therein. It has heretofore been the practice to dump the molds by hand upon their arrival at the dumping station, two or more attendants being frequently required for this purpose. We have provided for the automatic dumping of the molds. Our invention enables the dumping to be effectively and expeditiously carried out as the molds are conveyed to the dumping station, and eliminates the necessity and expense of dumping the molds manually. Another feature of the invention resides in provisions whereby any molds that have passed the pouring station without receiving the molten metal employed for casting are not dumped. In addition we provide for counting the molds dumped by the automatic dumping means so that an indication may be obtained of the total number of said molds. Other features of the invention will be hereinafter described and claimed.

In the accompanying drawings:

Fig. 1 is a view in side elevation of a portion of a mold-conveying apparatus to which has been applied an embodiment of our invention.

Fig. 2 is a plan view of the structure shown in Fig. 1.

Fig. 3 is a view of said structure, partly in front elevation and partly in vertical section, and

Fig. 4 is a vertical sectional view taken on line 4—4 of Fig. 1.

Referring to the drawings, there is shown at 5 a portion of an endless conveyor adapted to carry a series of molds. Conveyors of this type are employed in foundries for receiving molds at a mold forming station and conveying said molds past a pouring station, where the molds receive the molten metal to be cast and thence to a dumping station, where the molds are removed from the conveyor and dumped by hand. The conveyor comprises an endless chain and is engaged by a sprocket wheel 6 on a shaft 7 operated by any suitable means for driving the conveyor. As shown, the shaft 7 may be driven from a power

shaft through bevel gears 8, 9. Extending upwardly from certain of the links of the conveyor chain 5 are the studs 10, each pair of said studs passing through and being secured to a corresponding one of a series of plates 11. The latter, in traveling to and from the sprocket wheel 6, rest upon inner and outer rails 12, 13, respectively. Said rails are mounted on a suitable supporting frame work. The inner rails 12, as will be seen from Fig. 2, terminate short of said sprocket wheel. The conveyor is driven in the direction of the arrows in Fig. 2. As each plate 11, traveling to the left in Fig. 2, leaves the rails 12, it passes onto an annular rib 14 upon the sprocket wheel 6, which rib performs the function of an inner rail during the passage of the plate 11 over said sprocket wheel. Similarly as each plate 11 leaves the sprocket wheel 6 and travels to the right in Fig. 2, it moves out of contact with rib 14 and returns onto the rails 12. The outer rails 13 extend around the sprocket wheel as shown.

To provide for the automatic dumping of the molds we have shown each of the plates 11 provided with a pivotally mounted mold receiving or carrying plate 16. A hinge 17 connects each mold carrying plate 16 with a corresponding supporting plate 11. Projecting upwardly from each plate 16 is a bracket 18 having a bearing portion 19 into which a stem 20 carrying a roller 21 is adapted to be removably inserted.

Mounted adjacent the sprocket wheel 6 is a track-way 22 of inclined or cam formation. As shown, said track-way comprises two sections, 22', 22'', each extending upwardly and forwardly, which sections meet at their upper and outer ends, where they are secured to a bracket 23. The latter may be supported from a bar 24 projecting outwardly from a cross-beam 25, which cross-beam extends over sprocket wheel 6 and is mounted on supports 26, 27 on opposite sides of the conveyor chain. The lower outer ends of the cam track sections 22', 22''; respectively may be supported on brackets 28, 29 secured to bars 30, 31 depending from the beam 25. Said supporting bars 30, 31 may be rigidly connected at their lower ends by a cross

bar 32. The trackway 22 is so positioned as to be engaged by the rollers 21 of the respective mold carrying plates 16 as the latter travel with the plates 11 on the conveyor 5.

From the structure above described it will be seen that whenever a roller 21 of a plate 16 comes into contact with the trackway 22, the latter, as the travel of said plate continues, acts upon said roller to tilt said plate upwardly until, by the time the roller arrives at the highest point of the trackway said plate has been tilted sufficiently to dump the mold.

15 In Fig. 1, one of the plates 16 is shown tilted, the mold 34 thereon being shown sliding off said plate. Each of the plates 16 may be provided with a series of projections 35 for preventing the bottom boards 36 of the 20 mold from sliding off said plate when the latter is tilted. It will of course be understood that the cope and drag members surrounding each mold are removed therefrom by an attendant at an intermediate point in 25 the travel of the mold from the pouring station to the dumping trackway 22.

After the roller 21 of each plate 16 passes the highest point of the trackway 22 said roller rides down the trackway section 22", 30 and by the time said roller leaves said section the plate is again in its normal horizontal position. The plate then continues its travel with the conveyor to the molding station, where it receives another mold.

35 Each of the rollers 21 may if desired be permanently secured to the respective bracket member 18. By mounting the roller stems 20 removably in said bracket members, however, we provide for the dumping of only those 40 molds which have received metal at the pouring station. Any plate 16 which is not equipped with a roller will not engage the trackway 22 and will not be tilted. In addition, we provide for counting only the molds 45 that have received metal at the pouring station, or in other words, the molds that are dumped. Each roller stem is adapted, in passing the depending supporting bar 31, to actuate an arm 37 for operating a counting 50 mechanism contained in a casing 38 mounted on said bar. Said counting mechanism may be of any well known or standard construction and need not be here described, it being sufficient to note that said counter 55 is operated each time that a plate 16 equipped with a roller stem 20 passes by the operating arm 37. The counter is of course provided with the usual indicating dials so that the total member of roller-equipped plates 16, 60 which pass onto the trackway 22 may be noted at any time. It will thus be seen that if only those plates which carry molds that have received metal at the pouring station be provided with rollers 21, those molds which did 65 not receive metal for casting will neither be

70 counted nor dumped and will be preserved so that they may be filled upon returning to said station. At the same time, only those molds which have received said metal will be counted and dumped. The attendant charged with the duty of removing the cope and drag elements surrounding the molds may also see that only those plates 16 carrying molds that have received metal at the pouring station are equipped with rollers. 75 It will thus be seen that we have provided, not only for the automatic dumping of the molds, but also for the dumping of only those molds that should be dumped and that we have furthermore provided for counting 80 only the molds that are dumped. One advantage of our provisions for counting the molds is that a check is thereby afforded upon the total number of molds formed by the molders.

85 The roller stems 20 may be retained in the bearings 19 of the respective brackets 18 either frictionally or through any common form of detent or retaining means, such as a spring pressed ball engaging an aperture in the stem and yielding to permit withdrawal thereof from the bearing. Such detent means, being well known, need not be here described.

90 In Fig. 2 certain of the plates 11 traveling toward the sprocket wheel 6 have been shown without rollers, the molds on those plates having passed the pouring station without being filled. We have not deemed it necessary to show either the mold forming station or the 95 pouring station since said stations and their relation to the endless conveyor for the molds is well known in the art.

100 The terms and expressions which we have employed are used as terms of description and not of limitation and we have no intention, in the use of such terms and expressions, of excluding any mechanical equivalents of the features shown and described or portions thereof, but recognize that various structural modifications are possible, within the scope of 105 the invention claimed.

What we claim is:

110 1. In combination, a traveling conveyor, means on said conveyor for carrying various types of molds and means for automatically moving said carrying means relative to said conveyor during the movement of the conveyor to dump the mold when the latter arrives at a given point in the travel of the conveyor.

115 2. In combination, a traveling conveyor, means on said conveyor and movable therewith for carrying a separable mold and cam means for automatically operating said carrying means to dump the mold when the latter arrives at a given point in the travel of the conveyor.

120 3. In combination, a traveling conveyor, tiltably mounted mold supporting means car-

ried by said conveyor, and means for automatically tilting said supporting means transversely of said conveyor to dump the mold when the latter arrives at a given point in the travel of the conveyor.

4. In combination, a conveyor, mold supporting means on said conveyor, an element inclined with respect to the path of travel of said conveyor and mounted adjacent thereto, and means on said mold supporting means cooperating with said inclined member for effecting dumping of said mold during the travel of said conveyor.

5. In combination, a conveyor, mold supporting means on said conveyor, an element inclined with respect to the path of travel of said conveyor and mounted adjacent thereto, and displaceable means carried by said mold supporting means and cooperating with said inclined member when appropriately placed for effecting dumping of said mold during the travel of said conveyor.

6. In combination, a conveyor, mold supporting means on said conveyor, an element inclined with respect to the path of travel of said conveyor and mounted adjacent thereto, and means on said supporting means cooperating with said inclined member to effect tilting of said supporting means for dumping said mold during the travel of said conveyor.

7. In combination, a traveling conveyor, mold supporting means tiltably mounted on said conveyor, means for automatically causing tilting of said supporting means relative to said conveyor for dumping said mold during the travel of the conveyor, and means for retaining the bottom element of the mold on said supporting means during tilting of the latter.

8. In combination, a traveling conveyor, mold supporting means tiltably mounted on said conveyor, means associated with said conveyor and cooperating with said supporting means for automatically causing tilting of said supporting means for dumping said mold at a predetermined point in the travel of the conveyor, and projections on said supporting means for retaining the bottom element of the mold when said supporting means is tilted.

9. A mold dumping machine which comprises a continuously moving conveyor, mold supports carried by said conveyor and movable relative thereto, and means positionable on said supports for selectively controlling the movement of said supports for effecting selective dumping of the molds during movement of the conveyor.

10. A mold dumping machine which comprises a continuously moving conveyor, relatively stationary cam, mold supports carried by said conveyor and movable relative thereto, and means positionable on said supports adapted when properly positioned to cooper-

ate with said cam to control the movement of said supports and thereby selectively effect dumping of said molds during movement of the conveyor.

11. In combination, traveling mold conveying means adapted to receive different molds, supporting means for said conveying means, and cam means associated with said conveying means including a part carried by the conveyor and a part carried by the conveyor supporting means for automatically causing the dumping of said mold in the travel of the latter past a predetermined point.

12. In combination, a conveyor, a support therefor, mold supporting means on said conveyor, and mold dumping means including an element displaceably carried by said supporting means and a member carried by the conveyor support, said element when in a certain position cooperating with said member for automatically causing the mold to be dumped at a given point in the travel of said conveyor.

13. In combination, mold conveying means, means for automatically dumping molds carried by said conveying means, and means associated with said molds positionable at will to determine the effectiveness of said dumping means, whereby said dumping means may be controlled to avoid dumping empty molds.

14. In combination, mold conveying means, means for automatically dumping molds carried by said conveying means, means associated with the molds and positionable at will in cooperative or non-cooperative relation to said dumping means, whereby said dumping means may be controlled to avoid dumping empty molds, and counting means operable by said means associated with the molds for indicating the total number of molds dumped.

In testimony whereof, we have signed our names to this specification this 28th day of September, 1929.
